(57) **CLAIM**

We claim the ornamental design for a safe, as shown and described.

DESCRIPTION

FIG. 1 is a front perspective view of a safe showing the new design;
FIG. 2 is a rear perspective view of the safe of FIG. 1;
FIG. 3 is a top view of the safe of FIG. 1;
FIG. 4 is a front view of the safe of FIG. 1;

FIG. 5 is a rear view of the safe of FIG. 1;
FIG. 6 is a bottom view of the safe of FIG. 1;
FIG. 7 is a right side view of the safe of FIG. 1; and,
FIG. 8 is a left side view of the safe of FIG. 1.
In the drawings, the broken lines in FIGS. 1-5, 7 and 8 depict portions of the design that form no part of the claim.

1 Claim, 5 Drawing Sheets
